UNITED STATES PATENT OFFICE

162,230

MIRROR HANDLING TRUCK

Travis M. Sasser, Terrace Park, Ohio, assignor to Shipping Room Suppliers, Inc., Cincinnati,
Ohio, a corporation of Ohio

Application May 4, 1950, Serial No. 9,703

Term of patent 14 years

(Cl. D14—3)

To all whom it may concern:

Be it known that I, Travis M. Sasser, a citizen of the United States of America, residing at Terrace Park, in the county of Hamilton and State of Ohio, have invented a new, original, and ornamental Design for a Mirror Handling Truck, of which the following is a specification, reference being had to the accompanying drawing, forming a part hereof.

The figure is a perspective view of a mirror handling truck, showing my new design.

I claim:

The ornamental design for a mirror handling truck, as shown.

TRAVIS M. SASSER.
